DESCRIPTION

FIG. 1 is top-rear perspective view of an enclosure for a plug mounted network extender;

FIG. 2 is another top-rear perspective view of FIG. 1;

FIG. 3 is a top-front perspective view of FIG. 1;

FIG. 4 is another top-front perspective view of FIG. 1;

FIG. 5 is a bottom-rear perspective view of FIG. 1;

FIG. 6 is another bottom-rear perspective view of FIG. 1;

FIG. 7 is a bottom-front perspective view of FIG. 1;

FIG. 8 is another bottom-front perspective view of FIG. 1;

FIG. 9 is a left-side view of FIG. 1;

FIG. 10 is a right-side view of FIG. 1;

FIG. 11 is a rear view of FIG. 1;

FIG. 12 is a front view of FIG. 1;

FIG. 13 is a top view of FIG. 1; and,

FIG. 14 is a bottom view of FIG. 1.

The broken lines depict portions of the enclosure for a plug mounted network extender that form no part of the claimed design.
